ALBERT F. BANCROFT, OF WEST NEWTON, MASSACHUSETTS

DESIGN FOR A SHOE

Application filed August 25, 1932. Serial No. 44,694. Term of patent 3½ years.

To all whom it may concern:

Be it known that I, ALBERT F. BANCROFT, a citizen of the United States, residing at West Newton, in the county of Middlesex and State of Massachusetts, have invented a new, original, and ornamental Design for a Shoe, of which the following is a specification, reference being had to the accompanying drawing, forming part thereof, in which:

Fig. 1 is a plan view, and Fig. 2 is a view in side elevation, of a shoe showing my new design:

The dominant feature of my design resides in the ornamental effect produced by the connection of the opposite side portions of a vamp section in the rear of the tip by three straps, which are connected by a stay strap.

I claim:

The ornamental design for a shoe, as shown and described.

In testimony whereof, I have signed my name to this specification.

ALBERT F. BANCROFT.
